UNITED STATES PATENT OFFICE.

PAUL W. LAWTHER, OF DALLAS, TEXAS.

DESIGN FOR A WEIGHING-BIN.

43,051.

Specification for Design.

Patented Sept. 24, 1912.

Application filed June 11, 1912. Serial No. 703,080. Term of patent 14 years.

To all whom it may concern:

Be it known that I, PAUL W. LAWTHER, a citizen of the United States, residing at Dallas, in the county of Dallas and State of Texas, have invented a new, original, and ornamental Design for Weighing-Bins for the Use of Grocers, Confectioners, and Druggists, of which the following is a specification, reference being had to the accompanying drawing, forming part thereof.

The figure is a front view of a weighing bin for the use of grocers, confectioners, and druggists showing my new design.

I claim:

The ornamental design for a weighing bin, as shown.

PAUL W. LAWTHER.
